UNITED STATES PATENT OFFICE.

NISHAN M. BOYAJIAN, OF NEW YORK, N. Y.

DESIGN FOR A HAIR-HOLDER.

SPECIFICATION forming part of Design No. 30,461, dated April 4, 1899.

Application filed March 10, 1899. Serial No. 708,609. Term of patent 14 years.

To all whom it may concern:

Be it known that I, NISHAN M. BOYAJIAN, a citizen of Turkey, residing at New York, in the county of New York and State of New York, have invented and produced a new and original Design for a Hair-Holder; and I do hereby declare the following to be a full, clear, and exact description of the same, reference being had to the accompanying drawings, forming a part thereof.

My invention has relation to designs for hair-holders; and it consists in the novel construction and arrangement of its parts, as hereinafter described.

In the accompanying drawings, Figure 1 is a plan view of the holder, and Fig. 2 is a side elevation.

The leading feature of my design consists of a plain central portion 1, said central portion having the radial projections 2.

Having described my invention, what I claim as new, and desire to secure by Letters Patent, is—

The design for a hair-holder as herein shown and described.

In testimony whereof I affix my signature in presence of two witnesses.

NISHAN M. BOYAJIAN.
